GAUGE MECHANISM HOUSING

Eugene T. Sliwinski, Chicago, Ill., assignor, by
mesne assignments, to Charles J. Doyle, Hous-
ton, Tex.

Application October 24, 1946, Serial No. 134,199

Term of patent 14 years

(Cl. D52—1)

To all whom it may concern:

Be it known that I, Eugene T. Sliwinski, a citizen of the United States, and a resident of Chicago, in the county of Cook and State of Illinois, have invented a new, original, and ornamental Design for a Gauge Mechanism Housing, of which the following is a specification, reference being had to the accompanying drawing, forming a part thereof:

Figure 1 is a perspective view showing the front, one side, and top of a gauge mechanism housing, embodying my new design.

Figures 2 and 3 are elevational views of the other side and rear, respectively, of said housing.

I claim:
The ornamental design for a gauge mechanism housing, substantially as shown.

EUGENE T. SLIWINSKI.
